UNITED STATES PATENT OFFICE.

ODED SPENCER, OF JACKSONBURG, OHIO.

IMPROVEMENT IN STEAM-GENERATORS.

Specification forming part of Letters Patent No. 77,670, dated May 5, 1868.

To all whom it may concern:

Be it known that I, ODED SPENCER, of Jacksonburg, in Butler county, in the State of Ohio, have invented a new and useful Improvement in Steam-Boilers; and I do hereby declare that the following is a full and exact description thereof, reference being had to the accompanying drawings, and to the letters of reference marked thereon.

Figure 1 represents a top view of my improvement in boilers with the casing or upper portion of the furnace broken away. Fig. 2 represents a vertical sectional view of the boilers and furnace inclosing them.

In the accompanying drawings, A A A indicate the boilers, which are connected together by tubes B B above the water-line and by the tubes C C below the water-line.

D is an induction-pipe for the admission of feed-water, and b is the eduction steam-pipe.

The boilers may be made of any size, and any desired number may be connected in the manner represented in the drawings.

The furnace E may be made of brick-work or iron; but the construction will be such as to insure the complete envelopment of the boilers and their connecting-tubes in the flames and caloric generated by the burning fuel. The furnace is constructed of greater width than the length of the boilers, and suitable ledges or supports, d, are formed along the inner sides of the furnace, upon which the ends of the series of boilers rest.

The fuel is introduced through doors a a at the end of the furnace, and the arrows i i indicate the direction of the draft.

H H H are doors in the side of the furnace for the purpose of giving access to the man-holes in the ends of the boilers, and the doors I I I are for cleaning out the ashes.

The dotted line K denotes the undulating surface of the bottom of the furnace.

M is a damper to regulate the draft.

The rear end, O, of the furnace will be connected with a chimney in the usual manner.

My construction and arrangement of boilers for generating steam have the advantages of economy in the use of fuel and greatly cheapening the manufacture of boilers connected by induction and eduction tubes.

Heretofore the boilers arranged transversely over the fire-chamber have been connected by a long tube or pipe outside of the furnace and communicating with each boiler by a short connecting tube extending through the top of the furnace, and the water-pipe through which the boilers are fed was connected at the ends of the boilers in the same manner. I dispense with these two long pipes outside of the furnace and connect the boilers by the short tubes within the furnace. This new arrangement will diminish the quantity of fuel required, as the steam-tubes and water-tubes are subjected to the same degree of heat as the boilers, and consequently condensation of steam in exposed pipes is avoided.

One of the advantages of the short tubes arranged to connect the boilers is that it insures an equal supply of water at all times in the several boilers.

Having fully described my invention, what I claim, and desire to secure by Letters Patent, is—

The combination and arrangement of the boilers and tubes with the furnace E, whereby the entire surface of the boilers A and tubes B C is subjected to the action of the heat, substantially as and for the purpose specified.

In testimony whereof I have hereunto set my hand this 15th day of October, A. D. 1867.

ODED SPENCER.
